UNITED STATES PATENT OFFICE.

EZEKIEL C. CONDIT, OF KANSAS CITY, MISSOURI.

HEATING-FURNACE.

SPECIFICATION forming part of Letters Patent No. 334,644, dated January 19, 1886.

Application filed January 31, 1885. Serial No. 154,525. (No model.)

To all whom it may concern:

Be it known that I, EZEKIEL C. CONDIT, of Kansas City, Jackson county, Missouri, have invented a new and Improved Ventilating-
5 Heater, of which the following is a full, clear, and exact description.

My invention relates to heating apparatus that may be located directly within the room to be warmed and ventilated; and it consists
10 in the arrangement and combination of the various parts, as hereinafter described, and particularly pointed out in the claims.

The objects sought to be accomplished are increased economy in the consumption of fuel,
15 simultaneous control of improved ventilating devices, and general utility throughout the entire apparatus.

Reference is to be had to the accompanying drawings, forming part of this specification,
20 in which similar letters of reference indicate corresponding parts in each figure.

Figure 1 is a section through the apparatus upon the vertical line *zz*, Fig. 2; Fig. 2, a front elevation of the same; Fig. 3, a section upon
25 horizontal line *w w*, Fig. 1; Fig. 4, a section upon line *y y*, same figure; Fig. 5, a section on line *x x*, Fig. 1; Fig. 6, a section upon line *t t*, Fig. 1; Fig. 7, a section upon line *r r*, same figure; and Fig. 8 is a perspective view
30 of my improved fire-door.

In the construction of heaters or hot-air furnaces the draft-passages in most instances heretofore have been arranged to conduct the products of combustion in comparatively parallel lines toward the smoke-flue. This construction may allow the outgoing products sufficient velocity to prevent a great deposit of soot in the passages, which is commendable, being one of the strong points of my improved construction; but as such passages direct the heated products only in parallel lines toward the smoke-flue there is no force in operation to prevent a large proportion of radiable heat escaping with them.

45 In the improved furnace or heater shown in the drawings, by the peculiar arrangement of passages in the heating-drum A, a whirling motion is imparted to the hot gases, and, by reason of centrifugal force generated during such movement, they are made to impinge
50 constantly upon the outer radiating-surface,

A', of such drum. Heat that would otherwise be lost is thus retained and caused to pass through the radiating-surface, the remaining products passing to the smoke-flue A².

55

The drum A consists of a series of spiral passages, P, preferably four in number, encircling an annular passage, *g*, for hot air, and a direct-draft passage, A³, the whole being located directly above the fire-pot E. The upper extremity of each spiral passage P terminates in a chamber, A⁵, common to all. The lower end of the direct passage A³ is seated upon a neck, A⁴, located upon the upper portion of the fire-pot, and the lower extremity of each spiral passage P is placed in communication with the fire-pot by means of a neck or duct, *c*, formed integral therewith. An outer casing, B, incloses almost the entire radiating-surface of the apparatus, and is fitted with a cap, T, having perforations *l*, through which the heated air passes to the room. Openings *k*, for admitting air from the room to the interior of the casing, are formed in the casing just above the base-plate K', and are controlled by a register-plate, L. In practice there is an opening, K², in the room-floor beneath the base-plate K', communicating with the exterior of the building, and openings L²—for admitting fresh air—are formed in such base-plate inside the diameter of the casing B. These latter openings are controlled by a register plate or plates, L'. The register-plate L and the fresh-air plate L' are rigidly connected together by a suitable rod, N', or other means, and the handle N is common to both, the arrangement being such that when the room-openings K are closed the fresh-air openings L² will be open. Thus any movement of one plate is accompanied by a like and simultaneous movement of the other.

90

Heretofore in this class of heating apparatus the fresh-air register has been located at some distance therefrom, and its operation was inconvenient and uncertain. After the air enters the casing B, as before described, it comes in contact with the radiating-surfaces, and, being heated thereby, it passes upward through the space *a* between the casing and the drum A, and also through the space *g* between the drum and the direct passage A³. Short tubes or passages D reach through the

10

chamber A⁵ from the upper head, H, of the drum and form an outlet for the passage g. A damper, S', is located at a suitable point in the direct or central passage, A³, and is provided with an operating-handle, S, extending conveniently to the exterior of the casing B. When this damper is open, the products of combustion pass direct to the smoke-pipe A²; but when the damper S' is closed they must traverse the spiral passages P. The ash-pan b, front grate, G, and ash-box doors F may be operated in the usual manner.

Much inconvenience has heretofore been experienced in apparatuses of this class by reason of poorly-constructed fire-doors. For instance, hinges and other parts of the door were easily broken, and in replenishing the fire fuel would be scattered over the room-floor. These objections, among others, are obviated by my improved door M, which consists of a front plate, m⁴, having upon its outer face a longitudinal depression, f², engaging the casing B at the lower side, f, of the door-opening, and hinges f⁴, of ordinary construction, for holding the parts in position, and having upon its inner face segmental side pieces, O, cast integral therewith, and conforming to the radius of a circle having for its center the door-hinges, a lug, f', pro-

jecting upon the circumference of each side 30 piece, and adapted for contact with the upper side of the door-opening. When the door is thrown open, the front plate, M, is supported by the lugs f' in a position at about right angles to the casing B, and the two side 35 pieces, O, form a chute, through which fuel may be readily introduced.

Having thus described my invention, I claim as new and desire to secure by Letters Patent—

1. In combination with the fire-pot and the outer casing, a series of spiral passages connected to fire-pot and exit-flue, an annular hot-air passage encircled by the said spiral passages, and a direct-draft passage encircled by the hot-air passage, substantially as described.

2. The combination, in a hot-air furnace, of spiral passages, the annular hot-air passage, the direct-draft passage, a damper therein, the fire-pot having necks connecting with the several passages, and the outer casing provided with registers, substantially as described.

In testimony whereof I affix my signature in presence of two witnesses.

EZEKIEL C. CONDIT.
